UNITED STATES PATENT OFFICE.

LOUIS J. BERRY AND HARLEY SMITH, OF YALE, OKLAHOMA.

DESIGN FOR A KEY-RING.

56,116.

Specification for Design.

Patented Aug. 24, 1920.

Application filed February 27, 1920. Serial No. 361,660. Term of patent 14 years.

To all whom it may concern:

Be it known that we, LOUIS J. BERRY and HARLEY SMITH, citizens of the United States, residing at Yale, in the county of Payne and State of Oklahoma, have invented a new, original, and ornamental Design for a Key-Ring, of which the following is a specification, reference being had to the accompanying drawing, forming part thereof.

Figure 1 is a perspective view of a key ring, showing our new design, and

Fig. 2 is an edge view, showing our new design.

We claim:

The ornamental design for a key ring, as shown.

LOUIS J. BERRY.
HARLEY SMITH.
